UNITED STATES PATENT OFFICE.

GLENN E. EDMUND, OF COLUMBUS, OHIO, ASSIGNOR TO THE BONNEY-FLOYD COMPANY, OF COLUMBUS, OHIO, A CORPORATION OF OHIO.

METAL-CASTING MACHINE.

Application filed July 29, 1926. Serial No. 125,704.

This invention relates to improvements in metal casting machines of the type employed in connection with the casting especially of pig iron bars for ingots, and is principally directed to that type of a casting machine which is formed to include transversely spaced longitudinally extending endless chains which, in turn, are united by a plurality of longitudinally spaced transversely extending metal receiving molds, whereby upon the operation of the same the molds are presented to the discharge mouth of a reduction furnace, where the molds are filled with the molten metal and are then conveyed to a suitable point of discharge during which period the metal in the mold is allowed to cool and solidify.

Considerable difficulty has been encountered in machines of this character in the matter of providing for convenience and economy in repairs and replacements. In the past when one of the molds of the machine becomes cracked or broken or if a similar injury should happen to one of the mold supports used in connecting the ends of the mold with the adjoining chain, it has been necessary to stop the operation of the machine and take the same apart in order to remove and replace the broken or defective part. It is therefore, an outstanding object of the present invention to provide a novel and improved supporting fastening between the molds and their carrying chains whereby in the event of injury to either the molds or the mold supports, the defective part can be quickly and readily replaced without effecting the operative condition of the carrying chains.

Another object of the invention resides in constructing the links of the chain so that the latter will cooperate with the mold support to the end of maintaining the chain links in their proper transversely spaced positions and wherein there is but little loose play or relative movement between the links and the mold support, thus producing a structure wherein wear is reduced to a minimum and clogging metal deposit obviated.

Another object of the invention resides in the provision of a conveyor for machines of the type specified wherein the conveyor is formed to comprise a pair of longitudinally extending, transversely spaced links from which project laterally arranged lugs at the central longitudinal edge portions of the

links. In connection with this structure there is provided a mold support arranged to extend transversely of the links and provided with openings for the reception of the lugs on the links, the support, in turn, being formed with integral offset lugs arranged to engage the opposite side of said links so as to maintain the transverse spacing thereof, a removable locking pin being provided and removably positioned within transversely aligned openings provided in the sides of the links and the offset lugs of the mold support, the pin serving to removably lock the mold support in connection with the links without disturbing the operating positions of said links when the mold supports are being applied or removed. This latter feature is in distinct contrast with conveyors of previous design, wherein when the occasion has arisen to remove or replace a mold support it has been necessary to separate the links comprising the chain to effect the result. It has also been proposed to form the mold support integrally with the links with the result that if a single portion of the support becomes cracked or broken it is necessary to discard the entire structure. In the present invention great rigidity is secured in every way comparable with that of the integral construction and, in addition, a very considerable advantage is present in the fact that repairs and replacements can be made without stopping the operation of the machine and in very rapid time.

With these and other objects in view, as will appear as the description proceeds, the invention consists in the novel features of construction, combinations of elements and arrangements of parts hereinafter to be fully described and pointed out in the appended claims.

In the accompanying drawing:

Figure 1 is a plan view of one of the chain sections comprising the present invention, 100

Figure 2 is a side elevation thereof,

Figure 3 is a transverse sectional view on the line 3—3 of Figure 2,

Figure 4 is a longitudinal sectional view on the line 4—4 of Figure 1, 105

Figure 5 is a perspective view of one of the detachable mold supports,

Figure 6 is a detail perspective view of one of the link sections.

Referring more particularly to the draw-

110

ing the numeral 1 designates a conveyor chain formed in accordance with the present invention and especially adapted for use in connection with pig iron casting machines. The 5 chain is formed to comprise a plurality of interchangeable or reversible link sections 2, which may be used on either side of the chain, there being no right or left sections required. By this means I am enabled to use a single 10 pattern for the link sections on both sides of the chain. The link sections have the ends thereof provided with openings for the reception of transversely extending conducting pins 3, by which the adjoining ends of the 15 link sections are pivotally united together. Also, the link sections are provided with inwardly offset ends 4, permitting of convenience in the pivotal connection of adjoining link ends and at the same time producing a 20 very substantial design. Between the inwardly offset ends 4 of the links are disposed wheels 5, which are adapted to rotate about the pins or axles 3. The wheels 5 are suitably flanged, as is usual, for operation over 25 the trackway 6 of the casting machine. By this construction it will be seen that the chain will be permitted to flex and bend for passage around the drive and guide sprockets (not shown) of the machine, the flexing and 30 bending taking place without difficulty and in a manner common to chains of this type. It will be understood that in a pig casting machine two of these chains are employed, the said chains being transversely spaced and arranged for operation in vertical planes. Between these chains there is arranged a plurality of transversely extending longitudinally spaced metal receiving molds 7, which are attached to the chains 1 in a novel and 35 convenient manner to be hereinafter described.

Each of the link sections has the central and longitudinal edge portions thereof provided with integral perpendicularly extending lugs 8 lying in the plane of the body of each link section. These lugs are formed on the upper and lower edges of the links so that in the event of injury to one of the lugs the link may be reversed in its operating position to present a reserve lug thus enabling the use of the link as a whole to be continued.

Arranged to extend transversely across the link sections and positioned midway of the length of the links is a mold support 9. The 55 said support comprises preferably a flat metallic plate provided at one end with an opening 10 and at the opposite end thereof with a slot 11, which are adapted to receive the lugs 8 arising from the chain links. The 60 walls of the openings 10 and the slots 11 are formed to closely engage the adjacent walls of the lugs 8 so as to assist in rendering the construction exceptionally rigid. In carrying this object out still further, the mold support 9 is provided with a pair of transversely 65

spaced downwardly extending lugs 12, arranged to engage the inner walls of the spaced links 2 and, also, downwardly extending tongues 13 are provided upon one end of the mold support to engage the outer wall of the 70 adjacent links. By this arrangement each mold support serves to connect a pair of adjacent links so that the latter will be held firmly and securely, loose play largely eliminated and a non-wearing construction provided in which clogging metal deposit is reduced to a minimum. The walls of adjacent links, together with the lugs 12 are apertured for the removable reception of a locking pin 14, which serves to retain the mold supports 75 and associated molds in connection with the chains and prevents accidental removal or displacement thereof. The inner edges of the mold support are formed with openings 15 for the reception of securing devices 16 80 which serve to firmly connect the end of the molds 7 with the mold supports. Cotter pins 17 may be used for retaining the locking pins 14 in their applied positions.

In view of the foregoing it will be seen 90 that the present invention provides a conveyor chain wherein the mold supports may be removed from connection with the chain links without disturbing the operative position of the links in the chain assembly. This enables repairs and replacements to be made very quickly with but a slight loss in time. In fact, a defective mold can be replaced without stopping the operation of the machine. In previous constructions it has 95 been customary to slot the links and form the mold supports with outwardly directed tongues receivable within the slot. This construction, therefore, has necessitated the removal of individual links from the chain assembly to effect repairs, requiring the stopping of the machine and in addition considerable manual work in making the replacement. In the present construction this is all 100 obviated and a simple, rigid, readily replaceable and economical arrangement provided.

What is claimed is:

1. In a conveyor, a pair of longitudinally extending, transversely spaced links having the ends thereof formed for pivotal union with the corresponding end of similar adjoining links, said links being formed with integral laterally extending lugs on the central longitudinal edge portions thereof, a transversely extending mold support provided 115 with openings for the reception of said lugs, said supports being formed with integral offset lugs arranged to engage the opposite sides of said links to maintain the transverse spacing thereof, a transversely disposed locking pin receivable within aligned openings provided in the lugs of said links and the lugs of said mold support and serving to lock the latter in movable connection with said links.

2. In a conveyor, a pair of longitudinally extending, transversely spaced links, said links being provided with integral upstanding lugs along the central longitudinal edge 5 portions thereof, a transversely extending mold support bridging said links and having openings provided therein for the reception of said lugs, and a transversely disposed locking pin removably positioned within aligned openings provided in the lugs of said links and the lugs of said support. 10

In testimony whereof I affix my signature.

GLENN E. EDMUNDSON
